Specification of Letters Patent.

Patented Mar. 4, 1913.

Application filed June 17, 1912. Serial No. 764,080.

To all whom it may concern:

Be it known that we, MAX E. SCHMIDT and ALBERT J. FEARING, both citizens of the United States, and residents of the city, county, and State of New York, have jointly invented certain new and useful Improvements in Carriers, of which the following is a specification.

Our present invention, though useful in other respects, relates more particularly to improvements in that class of carriers now commonly known as "continuous-moving-platforms", for conveyance principally of passengers, and which consists essentially of a series of unitary members, or carriers, sequentially coupled to constitute a substantially continuous moving-platform, propelled by the rotation of a series of wheels disposed beneath the same, and upon the treads, or peripheries, of which the said carriers are supported upon rails secured to the latter, said treads being downwardly presented, and disposed, so as to bear upon, and coact with, the treads of said wheels in such manner that the rotation of the latter around their stationary axes causes the said rails, with their connected carriers, to advance with approximately the same speed of movement as the peripheries of said wheels.

Carriers of the type referred to are now well understood and have been described, for example, in United States Letters Patent No. 747,090, of December 15, 1903, and No. 763,421, of June 28, 1904, granted to one of us and George A. Mayland; and also in Letters Patent No. 939,334, of November 1, 1909, to one of us, and to the specifications and drawings of which patents reference may be had for more specific and detailed description of this class of carriers in its general aspects.

The objects of our present invention comprise provision of means whereby not only the required traction of the wheels on the rails is augmented and improved, and irregular wear of the wheels diminished, but also, and more particularly, means whereby the hitherto annoying, if not prohibitory, noise produced by such traction and wear, particularly in inclosures, or passages such as tunnels, is sufficiently diminished.

Experience has demonstrated that, in the particular types of moving platforms referred to, the hitherto prevailing construction of the treads of both the wheels and

tracks of the same kind of material, i.e. steel, both thus being equally unyielding, results not only in undesirable grinding, or slipping, of the thus mutually opposed surfaces, whence prohibitory unevenness in wear of such treads, involving jar-producing flattening, and speed-varying reduction, of peripheries, but also, causes, during propulsion of the platform, undesirable noises, including those of strident or percussive character. These, though endurable in open-air operation, are intensified by reverberation in inclosures such as tunnels, required in cities, etc. Obviation of these defects and discomforts has proved a difficult problem owing to the conditions imposed by special construction and requirements of operation characterizing moving platform systems. For example, imparting of peripheries of material softer than steel to the wheels has proved undesirable not only because directly decreasing, in prohibitive degree, the rapidity, and unevenness, of the wear of those parts which it is absolutely essential to maintain in their original integrity for required economy of power, effectiveness of traction, predetermined relative speeds of mutually adjacent platforms, and minimum noise. In such experiments the treads of the rails, being relatively unyielding, the weight thereby transmitted to the softer treads of the rotating wheels tends, in constantly accumulating degree, to distort, the latter from their required perfect circularity, thus intensifying the rapidity of their wear, and development of the other defects referred to.

We have finally been able to attain the said objects of our invention, thus remedying the defects referred to, by, broadly speaking, constructing the treads of the wheels of the hardest and least abrasive economically available materials, and, on the contrary, incorporating into the treads of the rails relatively more yielding material, 100 divided preferably into separate sections.

Forms of our said novel devices and expedients, and their relation to a moving platform system of the type referred to, are illustrated in the accompanying drawings, 105 in which—

Figure 1 is a plan or top view of a unitary carrier and of parts of two adjoining unitary carriers comprised in an indefinitely extended series of similar carriers 110

contained in a moving platform system of the type referred to; Fig. 2 is a transverse elevation of some of the load-supporting tractive wheels and their supporting parts of such a system, and showing also carriers of the type referred to and centrally disposed guide rails in vertical cross-section, taken on the dotted line $x-x$ of Fig. 1; Fig. 3 is a plan or top view showing the 10 construction of the frame, rails, and mutual inter-connections of the carriers shown in Fig. 1, their platforms or tops being removed for the purpose; Fig. 4 is a longitudinal vertical central sectional view, taken 15 on the dotted line $y-y$ of Fig. 2, looking in the direction of the arrow shown in that figure and showing certain elements and members in side elevation; Fig. 5 is a vertical longitudinal sectional detail view on enlarged scale taken on the dotted line $y-y$ of Fig. 6 seen in the direction of the arrow and showing one of our methods of securing our more yielding treads to the rail members; Fig. 6 is a transverse vertical 25 sectional view of Fig. 5, taken on the line $x-x$ of the latter, and seen in the direction of the arrow in that figure; Fig. 7 is a transverse vertical sectional detail view on enlarged scale, illustrating another of our 30 methods of securing the treads of more yielding material to the rail members; Fig. 8 is a view, similar to Fig. 7, showing still another of our said methods.

Similar reference letters in the various 35 figures refer to similar parts.

The moving or endless platform referred to is composed of a series of unitary carriers A , A' , each comprising a platform a for accommodation of the passengers and 40 rigidly secured thereto thereunder, and so supporting said platform, two rigid laterally-disposed rail-bearing members b , b' , having downwardly presented treads (see c , c' , c^2 , c^3 , Fig. 2). Prior to our present invention the members b , b' , have been constructed of metal—steel for example—and either of a single integral piece of such steel or of separate elements thereof combined and fortified as shown in the drawings, the 45 treads c , c' , etc., being also of steel. The said rail-members are so disposed as to be in alinement throughout the series when the carriers are coupled together and their ends on adjacent carriers are brought into such 50 close proximity to each other as to constitute, beneath the coupled unitary carrier platforms, as nearly as possible, two continuous downwardly-presented rail treads throughout the entire series. Each carrier 55 is provided with an extension or link d firmly secured as shown to its rail bearing members b , b' , below the level of its platform a and extending centrally and longitudinally beyond the latter. The said link 60 d is bolted or riveted to a brace i rigidly

secured to each of said rail-bearing members b , b' . The free terminal of the link d is provided with an eye-bearing member d' pivotally coupled to said link by a horizontal pivot to admit of some relative vertical movement between them. Each carrier is provided with a medially located coupling-pin e and also with a downwardly-extending projection n , located preferably below and concentric with said coupling-pin, and carrying the guide roller f rotatably secured thereto. The roller f is movably fitted in the interior of a continuous guideway or slot in a centrally disposed guide-rail g rigidly supported by frames h independently of the 70 carriers and their propelling mechanism. Support is afforded, and forward movement simultaneously imparted to the series of carriers by a plurality of wheels w , w' — w^2 — w^3 — w^4 — w^5 — w^6 — w^7 — w^8 — w^9 — w^10 — w^11 — w^12 — w^13 treads comprising preponderantly, or preferably composed entirely of, material more yielding than that constituting the treads of the wheels, *i. e.* more yielding than steel, if the latter be the constituent material of said last mentioned treads. We have, up to the present, found several such more yielding materials, more or less adapted to our purpose, as for instance more or less fibrous materials of vegetable or animal origin, such as wood, leather, hard rubber or compressed cotton. Natural wood, for instance, has proved much less favorable than other such substances, because of its insufficient uniformity and homogeneity in texture and density, it being particularly desirable that the material employed should be as homogeneous as possible, thus insuring greater uniformity of wear. Materials of other than vegetable or animal origin may also be employed, provided they are sufficiently cohesive integrally, examples of these being even metals more yielding than those constituting the peripheries of the wheels, as for example lead or alloys thereof, or of other metals. The particular material which we now prefer to employ in the treads of our rails to attain the objects of our invention is rubber in its various forms, or compositions of other ingredients with rubber, though experiments now making lead to the conclusion that much harder and less elastic and abrasive substances may be employed, with as good, if not better, results, the basic idea being that the constituent material of the treads of the rails shall be appreciably, though not greatly, more yielding, *i. e.* more compressible or impressionable, than the constituent material of the treads of the wheels. The said more yielding materials may be secured to the rail-members *b*, *b'*, in any convenient or preferred manner adapted to securely retain a substantial facing thereof in the treads under the strains imposed by operation of the referred to type of moving platform and its load. For example our, at present, preferred method of so securing to the rail members our comparatively yielding treads is shown in Figs. 5 and 6, in which *b* represents the lower part of one of such rail members. *c* is the tread, being a block of one of said more yielding materials, such as rubber for example. A shoe *o* is removably secured, as, by screw-bolts *o'*, to the bottom of the rail member carrying for that purpose thereto rigidly secured angle members *b* similarly secured in turn to frame members *b*, with the outside of which flanged portions of the shoe *o* normally contact and bear, the parts last mentioned being firmly held together, as will be readily understood, by the removable bolts *o'*. The shoe *o* is provided with a circumferential flange *o* which creates

a pocket or recess *o* in the downwardly presented interior of the shoe. The elements last mentioned, including said shoe, we construct preferably of steel, the same as the rail member *b*. The comparatively yielding material constituting the tread *c* is preliminarily shaped in any convenient manner to fill the pocket and recess *o*, to present a downwardly presented flat tread outside of said pocket, and to be bounded laterally by the same planes as those of the exterior of the shoe. The tread member *c* thus shaped is, when required, forced by pressure or otherwise to place, this being permitted by its shape and comparatively yielding character. Once in place, it is there retained, during operation of the moving platform, by reason of its shape and the construction of the shoe as above described. Each rail member *b* is provided with a plurality of shoes *o* which results in each rail carrying a plurality of separate sections, or separate treads, of the more yielding material, this plurality of separate sections being of great importance for reasons hereinafter mentioned.

It is obvious that other means, and ways, of securing the more yielding material to the rail members may be employed without departing from our invention. For instance, as indicated in Fig. 7, instead of providing the shoe *o* with the inwardly projecting flanges *o* and the resulting recess *o* of Figs. 5 and 6, a facing *p* of hard rubber may be caused to adhere to the shoe as by vulcanizing it thereto, and to said facing a block *p'* of softer rubber secured as by vulcanizing it in turn to said facing, such methods of attachment being well understood by those skilled in the art. Still another method of securing the block of more yielding material to the rail member *b*, the material being in this instance so slightly compressible as to prohibit its being driven into such a pocket as *o* of Fig. 5, is shown in Fig. 8, in which the shoe *o* is provided with downwardly extending circumferential flanges *o* thus providing a pocket or recess *o* of uniform aperture throughout, into which is introducible, with slight or substantially no compression, the block of last mentioned material which is removably held in place by bolts *o* passing through the block of material, the flanges *o* of the shoe and the frame members *b* of the rail member *b*, and secured in position by the screw-nuts *o*.

Though we have shown a variety of means for attaching the blocks of more yielding material to the rail members, it will of course be understood that we do not confine ourselves to any of these or to any particular way of securing the desired required connection.

The above-mentioned plurality of blocks of more yielding material secured to each of

the integral, or unitary, rail members so as to impart to latter a tread comprising a plurality of separate sections of such material is of particular advantage and importance 5 because relieving the treads of the accumulative distortion which might otherwise be disastrously imparted thereto, when thus composed of more yielding material, by the rotation of the tractive wheel against such 10 tread under pressure of the platform and its load. Such rotation, particularly when one of the opposed tread surfaces is of more yielding material than the other, results in lateral or longitudinal pressures upon the 15 constituent molecules of the former, which are thus, as it were, gradually compressed into a constantly accumulating wave caused by the pinch between the treads. This phenomenon occurs of course to a greater or less 20 extent proportionally according to the relative compressibility of one or other of the surfaces involved under the conditions mentioned, but it seems always in every case present and accounts, we believe, for much 25 of the undesirable disintegration and distortion of opposed treads under all conditions and as composed of any materials of differential yield. Our work in this field has demonstrated that the characteristic 30 mentioned prohibits the imparting of more yielding peripheries to the tractive wheels, as distinguished from the treads of the rails. In operation of endless platform systems and for attainment of the objects of our 35 present invention, we have found it impossible to impart such sectional construction with any industrial durability to the wheel surface owing to the nature and condition of the strains thereon imposed under the conditions mentioned. On the other hand we have discovered that the division of the 40 tread of the rails into a plurality of separate sections of material more yielding, than that of the treads or peripheries of the tractive wheels, is not only sufficiently durable 45 but also prevents effectively any prohibitory protraction of pinch between the treads with its resulting accumulation of molecules and consequent distortions of the 50 surface, accelerating wear, or destruction, of the treads, and also increasing undesirable noises.

We prefer to make the aforesaid sections quite short, say in the neighborhood of 24 55 inches in length, and they should be so proportioned with regard to the length of the unitary rail carrying them, and the distance apart of the axes of the tractive, or supporting, wheels of the moving platform system of the type employed as to insure, when 60 the wheels are not rotating and the platform is stationary, convenient removal from between the wheels of any one or more sections as may be required for repair or other 65 purposes. By thus dividing the tread of

our rail into a plurality of sections of the more yielding material it will be noted that the accumulation of pressure and accompanying distortion is limited to expire with the length of each such section 70 and is thus prevented from attaining such magnitude as to result disastrously. By this means the treads of the rails may be constructed of materials even as compressible as rubber, a heavy load carried, the tractive 75 wheels faced with unyielding material such as steel, and nevertheless sufficient durability for industrial purposes insured together with the other advantages referred to and hitherto comparatively unattainable 80 in this art.

It will be understood that the beneficial effects of our invention are not limited to identically the constructions shown in the drawings, but that, notwithstanding our 85 inventions are particularly useful in connection with such moving platform systems, they are also of advantage, under certain conditions, in ordinary surface railways in which the rails are stationary and the tractive load-carrying wheels are rotated around forward-moving axes; also that in such moving platform systems as are shown here at least the undesired noises produced by 90 idler load-carrying wheels in the system are diminished by combination therewith of our aforesaid rails equipped with treads of material more yielding than the peripheries of 95 said wheels.

What we claim as new and desire to secure by Letters Patent is the following, 100 viz:—

1. In a moving platform device the combination of a load-supporting, tractive, wheel rotatable around a stationary axis, a 105 movable, thereto-tangential, rail having a tread comprising material more yielding than that of the thereto opposed tread of said wheel, and means to rotate said wheel.
2. In a moving platform device the combination of a load-supporting, tractive, wheel rotatable around a stationary axis, a 110 movable, thereto-tangential, thereon down-bearing, rail having a tread comprising material more yielding than that of the thereto 115 opposed tread of said wheel, and means to rotate said wheel.
3. In a moving platform device the combination of a load-supporting, tractive, wheel rotatable around a stationary axis, a 120 movable, thereto-tangential, thereon down-bearing, rail having a tread comprising a plurality of separate sections of material more yielding than that of the thereto opposed tread of said wheel, and means to 125 rotate said wheel.
4. In a moving platform device the combination of a plurality of load-supporting, tractive, wheels each rotatable around a stationary axis, thereto tangential movable 130

rails carrying said platform and having a tread comprising material more yielding than that of the thereto opposed treads of said wheels, and means to rotate said wheels.

5 5. In a moving platform device the combination of a plurality of load-supporting, tractive, wheels each rotatable around a stationary axis, thereto tangential movable rails carrying said platform and having

treads comprising a plurality of separate 10 sections of material more yielding than that of the thereto opposed treads of said wheels, and means to rotate said wheels.
